DESIGN FOR A SEWING BOX

Harold W. Murray, San Pedro, Calif.

Application September 21, 1945, Serial No. 122,245

Term of patent 14 years

(Cl. D3--19)

To all whom it may concern:

Be it known that I, Harold W. Murray, a citizen of the United States of America, residing at San Pedro, county of Los Angeles, and State of California, have invented a new, original, and ornamental Design for a Sewing Box, of which the following is a specification, reference being had to the accompanying drawing, forming a part thereof wherein:

I claim:

The ornamental design for a sewing box, as shown.

HAROLD W. MURRAY.
